(57) **CLAIM**

The ornamental design for a headlight for cars, as shown and described.

DESCRIPTION

1. Headlight for cars
- 1.1 : Perspective
- 1.2 : Front
- 1.3 : Back
- 1.4 : Left
- 1.5 : Right
- 1.6 : Top
- 1.7 : Bottom

1.1 is a perspective view of a headlight for cars showing our new design; 1.2 is a front elevation view thereof; 1.3 is a back elevation view thereof; 1.4 is a left side elevation view thereof; 1.5 is a right side elevation view thereof; 1.6 is a top plan view thereof; and 1.7 is a bottom plan view thereof.
